CLAIM

The ornamental design for a therapeutic arm cover, as shown and described.

DESCRIPTION

FIG. 1 is a perspective view of the therapeutic arm cover as worn on the arm of an individual;

FIG. 2 is a left side view;

FIG. 3 is a front view;

FIG. 4 is a right side view;

FIG. 5 is a back view;

FIG. 6 is a top view, seen from the vantage point of view 6—6 in FIG. 3; and,

FIG. 7 is a bottom view, seen from the vantage point of view 7—7 in FIG. 3.

The different surface shading represents different textures on the surface of the article.
